ATTORNEY.

UNITED STATES PATENT OFFICE.

JULIUS DE LONG, OF BROOKLYN, NEW YORK.

ATTACHMENT FOR WINDOW-SASHES.

SPECIFICATION forming part of Letters Patent No. 427,977, dated May 13, 1890.

Application filed February 24, 1890. Serial No. 341,447. (No model.)

To all whom it may concern:

Be it known that I, JULIUS DE LONG, of Brooklyn, in the county of Kings and State of New York, have invented a new and useful 5 Improvement in Attachments for Window-Sashes, of which the following is a specification.

My invention relates especially to attachments for window-sashes, whereby the lower 10 sash may be raised a sufficient distance from the sill to permit a free passage of air over the top between the meeting-rails of the upper and lower sash for the purpose of securing ventilation for sleeping-rooms or other 15 apartments, while at the same time the space below the lower rail of the sash will be closed, preventing the ingress of air therebeneath.

To attain the desired end my invention 20 consists, essentially, in one or more leaves or plates adjustably connected to the lower rail of a window-sash, so arranged that they may be carried upward with the sash when the window is opened or permitted to slide down- 25 ward upon the rail and upon each other, closing the space beneath said rail when it is desired to raise the sash sufficiently to permit a free ingress of fresh air over the top rail, all of which will be hereinafter first fully de- 30 scribed, and then pointed out in the claims.

In the drawings, Figure 1 is an interior view of a window-sash wherewith my device is employed, showing the sash as shut down. Fig. 2 is a like view illustrating the sash as 35 raised. Fig. 3 is a sectional view at line $\alpha \alpha$ of Fig. 1.

Like letters of reference, whenever they occur, indicate corresponding parts in all the figures.

40 In the drawings I have shown but two slide- able leaves for convenience in illustration; but it is obvious that where the lower sash- rail is of considerable width one such leaf would be sufficient, whereas if it is found de- 45 sirable any number might be used without departing from the spirit of my invention. I have also shown the leaves as located upon the inner face of the sash-rail; but, if desired, these leaves might be concealed within the 50 rail and placed in a longitudinal groove or slot therein.

A is a window-frame; B, the lower sash, and C the upper sash.

D is a screw-threaded piece of metal se- 55 cured in the sash B at each side and arranged to receive thumb-screws E.

F is a plate or leaf of metal or wood extend- 60 ing across the sash. For clearness in illus- tration I have shown the plate as extending to the stops at the side of the sash; but it 65 may pass behind such stops or press closely against them. In plate F are slots H, through which the set-screws E extend. Beneath plate F is a second plate G, also slotted at I, in order to permit it to slide up behind 70 plate F.

K K are rivets secured near the lower edge of plate F and projecting through slots L in plate G, permitting the same to drop to the position indicated in Fig. 2 when the sash is 75 raised.

When constructed and arranged in accord- 80 ance with the foregoing description, my at- tachment will be found admirably adapted to the uses and purposes for which it is in- 75 tended. When not in use, by tightening the thumb-screws the plates are secured to the sash-rail, and may travel up and down there- with.

When it is desired to admit air to an apart- 85 ment having windows provided with my at- tachment, the thumb-screws are loosened, and when the sash is raised the lower edge of the plate or plates will rest upon the sill, prevent- 90 ing the passage of air beneath the sash, while it may freely pass over the top, throwing the current upward and preventing drafts at the bottom of the window.

I have illustrated a simple method of se- 95 curing the adjustable leaves in place and to each other; but this mechanical arrangement may be varied as desired.

Having now fully described my invention, what I claim as new therein, and desire to se- 95 cure by Letters Patent, is—

1. The combination, with the lower rail of a window-sash, of one or more adjustable leaves attached thereto and arranged to move therewith, substantially as and for the uses and purposes shown and described. 100

2. The combination, with the lower rail of a window-sash, of one or more leaves arranged

to slide downward when the sash is raised, or to be carried upward therewith, substantially as shown and described.

3. The combination, with the lower rail of
5 a window-sash, of one or more movable leaves
adjustably secured thereto by a thumb-screw
or its equivalent and arranged to travel with

the sash, substantially as shown and de-
scribed.

JULIUS DE LONG.
